UNITED STATES PATENT OFFICE

THOMAS A. HAZLETON, OF MACKSVILLE, KANSAS.

MATCH-SAFE.

No. 833,925.

Specification of Letters Patent.

Patented Oct. 23, 1906.

Application filed February 26, 1906. Serial No. 303,084.

To all whom it may concern:

Be it known that I, THOMAS A. HAZLETON, a citizen of the United States, residing at Macksville, in the county of Stafford and State of Kansas, have invented certain new and useful Improvements in Match-Safes, of which the following is a specification.

This invention relates to an improved match-safe of that character which is constructed so as to form a receptacle having communication with a trough into which the matches are fed so as to be readily removed by means of the fingers.

The object of the invention is to provide a match-safe which is so designed as to be extremely rigid in its construction and so that it can be manufactured at a comparatively small cost.

A further object is to provide means for regulating the feeding of the matches into the trough.

For a full description of the invention and the merits thereof and also to acquire a knowledge of the details of construction of the means for effecting the result, reference is to be had to the following description and accompanying drawings, in which—

Figure 1 is a perspective view of the improved match-safe. Fig. 2 is a vertical sectional view through the same. Fig. 3 is a transverse sectional view. Fig. 4 is a horizontal sectional view through one of the outer corners of the trough. Fig. 5 is a perspective view showing the method of cutting and bending the back of the receptacle for attaching the hanger.

Corresponding and like parts are referred to in the following description and indicated in all the views of the drawings by the same reference characters.

In the simple form of the invention the match-safe comprises a receptacle 1 and a trough 2 at the lower end thereof, into which the matches are fed. This receptacle 1 is formed of a piece of sheet material which is bent so as to form the front 3, sides 4, and has its edges connected in the rear by means of a joint formed by bending them back upon themselves, so as to form hooks which engage with each other. A pair of tongues or ears 5 are formed by cutting the middle of the lower portion of the front 3, and these ears 5 are bent outwardly, so as to lie flush with the sides 4. The lower edges of the receptacle are bent to form the outwardly-extending flanges 6, and the edges of the bottom 7 are

bent back upon themselves so as to embrace the flanges 6. The forward portion of the bottom 7 is bent upwardly at 8 to form the front of the trough 2, and the sides of the upwardly-bent portion 8 are connected to the front of the tongues 5 by means of a joint or seam similar to that just described in connection with the back of the receptacle. The upper edge of the upwardly-bent portion 8 is folded back upon itself at 9, so as to eliminate any sharp edge upon which the fingers might be injured, and it will also be observed that this portion 8 is provided at an intermediate point with a notch or slot 10. This slot 10 extends into the forward portion of the bottom 7 and enables the matches in the trough 2 to be readily removed by means of the fingers. A hanger 11 is secured to the back of the receptacle 1 and forms a means by which the device can be conveniently suspended upon the wall. In order to connect the hanger 11, cuts 12 are made in the rear corners of the receptacle and the upper edge of the back bent inwardly and downwardly. The lower edge of the hanger 11 is then bent rearwardly and upwardly, so as to engage with the downwardly-bent portion of the receptacle. By this construction a joint 13 is obtained which rigidly connects the hanger to the match-safe in such a manner as to sustain any weight which may be imposed upon it. An essential feature of this joint 13 also resides in the fact that the sides of the hanger 11 flare outwardly from the joint and engage with the bottom of the cuts 12, so as to prevent the hanger from being pushed downward in order to break or disconnect the joint 13. It will also be observed that the upper corners of the sides 4 adjacent the cuts 12 bear against the hanger and tend to prevent the same from being bent forwardly and that the joint 13 has a similar tendency to prevent the hanger from being bent to the rear. In the formation of the joint 13 it will be observed that the portion of the back of the receptacle containing the seam is not bent downwardly, but is cut away, as seen at 14. The upper portion of the hanger 11 may be given any ornamental shape, as shown in the drawings, the only restriction being that the sides flare outwardly for the purpose mentioned.

In order to regulate the feeding of the matches from the receptacle 1 into the trough 2, a gate 15 is provided, which is slidably mounted upon a plate 16, secured to the

inner side of the front 3. The upper and the lower edges of the plate 16 are bent outwardly, so as to embrace the front 3, as seen at 17, and these outwardly-bent portions 5 may also serve to hold a match-scratching surface, such as a piece of sandpaper 18, in position. The sides of the plate 16 are bent inwardly to form a guideway within which the gate 15 slides. It will thus be apparent 10 that by lowering the gate 15 the flow of the matches into the trough can be checked, and vice versa. In the operation of the device the matches are placed in the receptacle 1 in the usual manner and permitted to automatically feed into the trough 2 as they are 15 removed from the latter.

A throat is formed at the lower portion of the receptacle 1 and just above the trough 2, and this throat tends to throw the matches 20 toward the forward end of the trough and to prevent them from becoming crossed, so as to choke the flow. For this purpose a plate 19 is employed, which is preferably an extension of the upwardly-bent portion 8 of the 25 bottom 7, and which extends rearwardly and upwardly along the bottom and feeds the matches toward the forward end of the trough. A plate 20, secured to the gate 15 and projecting inwardly, coöperates with the 30 plate 19 to form a throat for the purpose mentioned, and the width of the throat can be regulated by raising and lowering the gate 15 and the flow of matches thus regulated.

Having thus described the invention, what 35 is claimed as new is—

1. In a device of the character described, the combination of a receptacle formed of sheet material and having the upper edge of the back thereof bent downwardly, and a 40 hanger having its lower edge bent upwardly so as to engage with the before-mentioned downwardly-bent edge upon the receptacle, the sides of the hanger flaring outwardly from the bottom and engaging with the two 45 sides of the receptacle adjacent the back to

prevent the hanger from being pushed downwardly so as to be disconnected from the receptacle.

2. In a device of the character described, the combination of a receptacle, a trough at 50 the lower end of the receptacle and having communication therewith, a plate having its upper and lower edges bent back upon themselves so as to embrace the front of the receptacle against which the plate fits, and a gate 55 slidably mounted upon the plate and adapted to be raised and lowered to regulate the flow from the receptacle to the trough.

3. In a device of the character described, the combination of a receptacle, a trough at 60 the lower end of the receptacle and having communication therewith, a plate having its upper and lower edges bent back upon themselves to embrace the front of the receptacle against which the plate fits, and a gate, the 65 sides of the plate being bent inwardly to form a guideway within which the gate is slidably mounted, the said gate being adapted to be raised and lowered to regulate the flow from the receptacle to the trough. 70

4. In a device of the character described, the combination of a receptacle, a trough at the lower end of the receptacle and having communication therewith, a plate extending rearwardly and upwardly along the bottom 75 of the trough so as to throw the matches toward the forward end of the trough, a gate slidably mounted upon the front of the receptacle and adapted to be raised and lowered to regulate the flow of the matches from the receptacle to the trough, and a second plate secured to the gate and projecting inwardly so as to coöperate with the first-mentioned plate. 80

In testimony whereof I affix my signature 85 in presence of two witnesses.
